ATTORNEY

UNITED STATES PATENT OFFICE.

EUGENE F. UTZ, OF MIDDLETOWN, OHIO.

CARBURETOR.

1,416,913.

Specification of Letters Patent. Patented May 23, 1922.

Application filed March 6, 1918. Serial No. 220,777.

To all whom it may concern:

Be it known that I, EUGENE F. UTZ, a citizen of the United States, residing at Middletown, in the county of Butler and 5 State of Ohio, have invented certain new and useful Improvements in Carburetors, of which the following is a specification.

The broad idea of the present invention is to enrich the mixture flowing from a carburetor in proportion as the temperature of the 10 water in a cooling jacket of an internal combustion engine falls.

This is carried out by jacketing a thermal bar so that it will expand and contract with 15 the rise and fall of the temperature of the water, and providing almost any ordinary type of carburetor with an auxiliary gasoline nozzle whose opening and closing movements are controlled by the action of said 20 thermal bar.

Details of my preferred manner of carrying out the invention are set forth below, and shown in the drawings, wherein:—

Figure 1 is a general vertical section of 25 this entire device, showing the thermal element diagrammatically only.

Figure 2 is a sectional detail to be referred to hereinafter.

In the type of carburetor shown herewith, 30 gasoline enters at 1 into a float chamber 2 and raises and lowers the float 3 which in turn controls a needle valve 4 to shut off the admission of gasoline when enough or too much has been supplied. From the 35 float chamber the gasoline flows along a passage 5 to and through the main nozzle 6 whose opening is controlled as usual at 7. Air is admitted at 8, and sometimes through the air valve 9 which is controlled as at 10. The numeral 11 designates the butterfly 40 valve, and 12 is the outlet to the intake manifold of the engine, not shown. Thus is briefly described the construction of any well known type of carburetor, and as far 45 as this element is concerned, my present invention consists in the provision of an auxiliary nozzle 15 opening from the passage 5 and controlled by a vertically movable needle valve 16 normally raised by a spring 17.

50 Therefore, when whatever opposes this spring is removed or the pressure thereon released, the spring will cause the opening of the valve so that the nozzle 15 admits gasoline in addition to that admitted by the 55 main nozzle 6, with the result that the mix-

ture is enriched where it flows at 12 to the engine.

In Figure 1 I have diagrammatically shown a thermal element which is employed in connection with this invention. The 60 same might be said to consist of a bar 20 of hard rubber or the like disposed between water legs 21 and 22 which are respectively connected as at 23 and 24 to the water cooling system of an internal combustion engine. Whatever the arrangement, when the 65 temperature of the water in this system rises, the thermal bar 20 expands for purposes yet to appear. One end of this bar is fixed, and the other carries a hook 25 bearing against one arm of a bell-crank lever 26 pivoted at its angle at 27 to some fixed support, and the other arm of this bell-crank lever has a hole 28 loosely engaging a set screw 29 mounted in the upper end of the 75 needle valve 16 as best seen in Figure 2.

With this construction, when the car is running or the temperature of the water is normal, the thermal bar 20 has expanded sufficiently to let the valve 16 descend and close 80 the auxiliary nozzle 15. Now when the weather grows cold or the engine becomes idle or perhaps gets quite cold by standing over night, the water legs 21 and 22 become cool or cold and the thermal bar 20 contracts. The 85 result is that its hook 25 allows the bell-crank lever to turn on its pivot under the influence of spring 17 and the arm 23 thereof raises the valve 16 so as to open the auxiliary nozzle 15 and permit a little more gasoline to flow 90 into the mixing chamber than can pass through the main nozzle 6. Therefore the cold engine will be supplied with a richer mixture for running or for starting, and the supply is automatically controlled whatever 95 the change in temperature. Manifestly the invention is susceptible of considerable change in the matter of details of construction, and obviously it could be applied to many types of carburetors and the auxiliary 100 nozzle could be actuated by many forms of thermal elements; so long as the latter are actuated by variations in the temperature of the water or other cooling agent.

What is claimed as new is:—

105
In combination with a carburetor, a main gasoline nozzle, an auxiliary gasoline nozzle vertically extending through the air chamber from a horizontal conduit from the bottom of a float chamber, said conduit supply- 110

ing both said nozzles, a needle valve for closing the auxiliary nozzle, said needle valve including a stem having an interiorly threaded socket in its upper end, a set-screw 5 adjustable in said socket, a spring for normally holding the needle valve in open position, a bell crank lever pivotally connected to the carburetor with one arm vertical and one arm horizontal and having an elongated opening in its horizontal arm through 10 which the set screw passes, a horizontal thermal bar fixed at one end and having its other end engaged with the vertical arm of the bell-crank lever, and water legs on opposite sides

of said thermal bar and in circuit with the 15 cooling system of an internal combustion engine, said float chamber of substantially the height between said horizontal conduit and the top of said auxiliary nozzle stem and unitary with the housing for the said elements and provided on its top with a seat to receive said thermal bar.

In testimony whereof I affix my signature in presence of two witnesses.

EUGENE F. UTZ.
